UNITED STATES PATENT OFFICE.

BERNIE BROOKS, OF ST. LOUIS, MISSOURI.

COLLAR-FASTENER.

1,273,325.

Specification of Letters Patent. Patented July 23, 1918.

Application filed June 6, 1917. Serial No. 173,105.

To all whom it may concern:

Be it known that I, BERNIE BROOKS, a citizen of the United States, residing at the city of St. Louis and State of Missouri, have 5 invented a new and useful Collar-Fastener, of which the following is a specification.

This invention relates to a new and useful collar fastener, and consists in the novel construction hereinafter specified.

10 The object of the invention is to produce a simple and efficient collar fastener for holding the flaps of a turned over soft collar together; which fastener may be readily applied and removed and may be worn without 15 discomfort and will remain in place when worn.

With the foregoing object in view, I have produced the collar fastener hereinafter disclosed, reference being made to the accompanying drawing, in which—

20 Figure 1 is a front view of a collar having the fastener of the present invention applied thereto.

25 Fig. 2 is a side view of the collar illustrating the fastener applied thereto.

Fig. 3 is a section through the collar viewing the fastener of the invention in plan applied to the collar.

30 Fig. 4 is a perspective view of the fastener.

Heretofore it has been usual in holding together the flaps of a soft collar to use a bar pin of the safety type with the prong extending in a straight line beneath the flaps.

35 This method of fastening a collar has two important disadvantages, the first is that a pin of the type referred to is very uncomfortable to the wearer, as the inner prong presses against the neck, and the other is 40 that the collar is pulled out of shape and the flaps appear uneven. The difficulty of applying the fastener of the type referred to has also militated against its use.

The fastener of the present invention obviates the above disadvantages, it being accurately designed so that it may be worn with comfort, and so that it may be applied with facility and when applied will hold the flaps of the collar perfectly even.

50 The collar with which the fastener is intended to be used is of a familiar type comprising a turned over portion having the flaps 2 and 3. The fastener consists of a relatively long and narrow bar 4 curving to 55 the contour of the collar on the wearer. The two prongs 5 are in connection with the

inner or concave side of the bar at relatively a considerable distance from the ends of the bar, leaving extended portions of the bar beyond said prongs for engagement by the 60 thumb and finger of the wearer in attaching the bar to the collar and detaching the bar from the collar. These extended portions of the bar also contact with the collar and assist in preventing the prongs from 65 working loose as occurs in the case of fasteners of different types. The points of the bar lie on a line substantially conforming with a line or cord drawn between the extended ends of the bar 4. I have found that 70 a fastener of this construction may be readily engaged by the thumb and finger and that the fastener may be easily connected with the collar without the collar being pressed away from the bar by the thumb 75 and finger as would occur if the prongs 5 were at the ends of the bar 4.

The fastener is adjusted on the collar by first embedding one of the prongs 5 through one of the flaps of the collar and drawing 80 the flaps together with a slight strain embedding the other prong in the opposite flap. The pressure holds the fastener firmly in place, preventing the accidental displacement of the same.

85 In order to remove the fastener it is necessary to disengage one of the prongs by moving it longitudinally of the flap against the normal strain on the collar. The fastener can not be pulled out by a direct forward 90 pull due to the angle and curve of the prongs 5. As the bar 4 conforms to the natural curve of the collar and as the prongs 5 extend only for a slight distance there is no part of the fastener that exerts pressure 95 against the neck of the wearer.

From the foregoing the essentials of the construction and the advantages attainable thereby will be readily apprehended.

I claim:

1. A collar fastener, comprising a relatively long and narrow bar, and a single prong attached to the inner face of the bar at relatively a considerable distance from each end of the bar leaving an extended portion of the bar beyond each of said prongs for engagement by the thumb and finger of the wearer in attaching the bar to the collar and detaching the bar from the collar.

2. A collar fastener, comprising a relatively long and narrow bar curving to the contour of the collar on the wearer, and hav-

ing its inner surface in the same curved plane throughout its length, and a pair of prongs in connection with the bar at relatively a considerable distance from the ends 5 of the bar leaving extended portions of the bar beyond said prongs for engagement by the thumb and finger of the wearer in at-

taching the bar to the collar and detaching the bar from the collar, said prongs having their points terminating approximately in 10 the same plane with the ends of the bar.

In witness whereof, I have signed this specification.

BERNIE BROOKS.
